UNITED STATES PATENT OFFICE.

CHARLES F. WELDON, OF DELAVAN, WISCONSIN.

MECHANICAL INKING APPARATUS.

Application filed September 11, 1923. Serial No. 662,102.

To all whom it may concern:

Be it known that I, CHARLES F. WELDON, a citizen of the United States, residing at Delavan, in the county of Walworth, State 5 of Wisconsin, have invented a new and useful Mechanical Inking Apparatus; and I do hereby declare the following to be a full, clear, and exact description of the invention, such as will enable others skilled in the art 10 to which it appertains to make and use the same.

The invention relates to mechanical inking devices for printing presses and has for its object to provide a device of this character 15 wherein a stirrer is automatically moved, longitudinally, through the ink fountain of a press adjacent the fountain roller, thereby insuring a feeding of ink of uniform consistency to the roller and prevent the formation of scum and the like on the ink.

A further object is to provide an agitator for printing press fountains, which may be easily and quickly applied to a printing press fountain without varying the construction 20 of the press or fountain.

A further object is to provide a printing press fountain agitator comprising a horizontally movable agitator mounted on a guide rod, a feed screw extending through 25 said agitator and adapted to move the agitator longitudinally for stirring ink within the fountain adjacent the fountain roller and to provide a reversing mechanism adjacent one end of the fountain, which reversing mechanism is controlled by a rod 30 having stops in the path of stops carried by the agitator, and forming means whereby the direction of rotation of the feed screw will be changed as the agitator approaches 35 the end of its movement.

A further object is to provide spring mounted stops carried by the agitator for shifting the reversing gear mechanism, and allowing the reversing mechanism to easily 40 shift.

With the above and other objects in view the invention resides in the combination and arrangement of parts as hereinafter set forth, shown in the drawing, described and 45 claimed, it being understood that changes in the precise embodiment of the invention may be made within the scope of what is claimed

without departing from the spirit of the invention.

In the drawings:

Figure 1 is a top plan view of a conventional form of printing press fountain, showing the agitating device applied thereto.

Figure 2 is a side elevation of the printing press fountain and agitating device.

Figure 3 is a top plan view of the reversing mechanism.

Figure 4 is a sectional view taken on line 4-4 of Figure 1.

Referring to the drawing, the numeral 1 designates the fountain of a conventional form of printing press and 2 a fountain roller which takes up the ink from the fountain and transfers it to printing mechanism in the usual manner. Secured to the under side of the fountain 1 by means of bolts 3 are rearwardly extending brackets 4 and 5, which brackets support the mechanism hereinafter set forth. The brackets 4 and 5 are provided with slots 6 for the reception of the bolts 3 so that the brackets may be easily and quickly applied and the bolts 3, which are standard bolts carried by the fountain 1 are utilized for supporting the device on the fountain without the necessity of modifying the construction of the fountain while boring additional holes. Bracket 5 terminates in a rearwardly extending horizontally disposed plate 7, which plate supports the motor 8 and the gear casing 9, in which reversible clutch mechanism is disposed. Rigidly supported in eyes 10 carried by the upper side of the gear casing 9 and the bracket 4 is a horizontally disposed guide rod 11 which is preferably hollow, and on which guide rod the agitator block 12 is slidably mounted, which block supports the agitator arm 13, which extends into the fountain 1 to a point adjacent the fountain roller 2. During the operation 95 of the device the agitator arm 13 moves longitudinally through the fountain 1 from one end to the other thereof, thereby agitating the ink and thoroughly mixing the same, consequently ink taken up by the fountain 100 roller 2 is of uniform consistency and color, and consequently the printing produced by the press will be uniform as to shade. Disposed beneath the guide rod 11 is a feed

screw 14, which screw is threaded through the agitator block 12, and consequently when rotated will move the guide block and agitator carried thereby longitudinally according to the direction of rotation of the feed screw. The feed screw 14 at one of its ends is mounted in a bearing 15 of the bracket 4 and the other end rotatably mounted in bearings 16 of the gear casing 9. Rotatably mounted on the feed screw 14 inside the gear casing 9 are gears 17 and 18, which gears are provided with clutch members 19 and 20, with which the clutch members 21 and 22 carried by the slideable clutch element 23 cooperate for imparting rotation to the feed screw 14 in opposite directions according to the position of the clutch element 23, for instance by referring to Figure 3 the gear 18 and the shaft 14 are rotating in the direction of the arrow *a* at which time the agitator arm is moving in the direction of the arrow *b*. Under these conditions the member 20 of the gear 18 is in engagement with the member 22 of the clutch element 23, therefore the shaft 14 rotates in the direction of the arrow *a*. Slidably mounted in bearings 24 of the bracket 4 and the gear casing 9 is a shift rod 25, which shift rod is provided with a clutch yoke 26 which engages the clutch element 23, and when the shift rod is moved longitudinally the clutch members 19 and 21, and the clutch members 20 and 22 are moved into and out of cooperative position at the ends of the stroke of the agitator arm 13. Adjustably mounted on the shift rod 25 adjacent its end are fingers 27, which fingers are in the path of resiliently supported members 28 carried by the block 12, therefore it will be seen that as the members 28 come into engagement with the fingers 27 adjacent the ends of the strokes of the agitator 13, the shift rod will be shifted longitudinally according to the direction of movement of the agitator arm and consequently the clutch yoke 26 will be shifted for rotating either gear 17 or 18 thereby changing the direction of rotation of the feed screw 14 and consequently insuring positive reciprocation of the stirrer 13 in the fountain 1 during the operation of the device. By resiliently mounting the members 28 against the springs 29, it will be seen that banging of the device at the ends of the strokes will be obviated and sufficient play allowed to take care of the period of time necessary for the shifting of the clutch element 23 by the yoke 26.

Rotatably mounted in the gear casing 9 is a drive shaft 30, which drive shaft is provided with a universal connection 31 with the drive shaft 32 of the motor 8 and is constantly driven by said motor in the direction of the arrow *c*, thereby imparting rotation to the gear 18 in the direction of

the arrow *a* at all times, however the feed screw 14 is not rotated except when the clutch element 23 is in the position shown in Figure 3. Drive shaft 30 is provided with a gear 33 which meshes with a gear 34 carried on a counter shaft 35 and which gear 34 drives a gear 36 carried by a second counter shaft 37, thereby forming a gear train between the drive shaft 30 and the gear 18, with which the gear 36 meshes, thereby driving the gear 18 in the direction of the arrow *a* and the feed screw 14 in the same direction and the clutch element 23 is in the position shown in Figure 3. When the shift rod 25 is shifted by the agitator reaching the ends of its movement in the direction of the arrow *b* the clutch element 23 is moved into cooperative relation to the gear 17, which is idly mounted on the feed screw 14, however as the clutch element 23 is slidably keyed to the feed screw 14, the gear 17 which rotates in the direction of the arrow *d* will rotate the clutch element and the feed screw 14 in the direction of the arrow *b* at an opposite direction to the previous operation of the screw, therefore the agitator arm 13 will be moved in the direction of the arrow *e*, the above operation continuing during the operation of the device. Idle gear 17 is rotated in the direction of the arrow *b* by means of a gear 38 carried by the counter shaft 35 and consequently it will be seen that the gears 17 and 18 rotate constantly in opposite directions during the operation of the motor 8.

From the above it will be seen that an automatic ink stirring device is provided for printing presses wherein the ink in the fountain will be thoroughly stirred and uniformly distributed on the fountain roller at all times, and one which may be easily and quickly applied to a printing press without varying the construction of the press.

The invention having been set forth what is claimed as new and useful is:

1. The combination with an ink fountain of a printing press, of an ink agitating device therefor, said device comprising an agitating member, a feed screw, a guide rod, said agitating member being mounted on said feed screw and guide rod, a power shaft, gear and clutch connections between the power shaft and feed screw, a clutch control rod slidably mounted and normally independent of the agitating member, adjustable stops carried by said clutch control rod and yieldably mounted stops carried by the agitating member in the path of the adjustable stops.

2. The combination with a printing press fountain agitating device, said device comprising an agitating member, a feed screw on which the agitating member is mounted,

means for rotating said feed screw, clutch means for intermittently reversing the direction of rotation of the feed screw, of an independent slidably mounted clutch control rod, spaced stops carried by said clutch control rod at opposite sides of the agitating member, and yieldable members carried by the agitating member in the path of the spaced stops and forming means for reversing the direction of rotation of the feed screw through the clutch.

In testimony whereof I have signed my name to this specification in the presence of two subscribing witnesses.

CHARLES F. WELDON.
